DECORATIVE PROTECTIVE HOUSING FOR ELECTRICAL FIXTURE

Jack A. Meltzer, 3398 Fairway Road,
Oceanside, N.Y. 11572

Filed Apr. 12, 1968, Ser. No. 11,441

Term of patent 14 years

Int. Cl. D26—06

U.S. Cl. D48—16

I claim:

The ornamental design for a decorative protective housing for electrical fixture, substantially as shown.
